UNITED STATES PATENT OFFICE.

LOUIS BULASKY, OF NEW YORK, N. Y.

SEWING-MACHINE.

No. 929,119.

Specification of Letters Patent. Patented July 27, 1909.

Application filed August 8, 1908. Serial No. 447,504.

To all whom it may concern:

Be it known that I, LOUIS BULASKY, a citizen of the United States residing in the borough of Manhattan, of the city of New York, in the State of New York, have invented certain new and useful Improvements 5 in Sewing-Machines, of which the following is a specification, reference being had to the accompanying drawings, forming a part 10 hereof.

This invention relates generally to sewing machines of the character of that disclosed in Letters Patent of the United States No. 777,074, dated December 13, 1904, which 15 machines are mainly used in the stitching of silk-, cotton- and paper-covered wire at the edges of buckram hat frames and felt hats, and for other purposes.

The general object of the invention is to 20 improve the efficiency, adaptability for various uses, and convenience in operation of machines of this character, and it consists more particularly in certain improvements 25 in various parts of such machine, all as will be more particularly referred to hereinafter.

In the drawings in which the several improvements are illustrated as embodied in a machine of suitable and convenient construction—Figure 1 is a view in side elevation of 30 such a machine. Fig. 2 is a top view thereof. Fig. 3 is an end elevation as seen from the left hand in Fig. 1. Figs. 4 and 5 are respectively a top view and a view partly in horizontal section of the work guide or gage. 35 Fig. 6 is a detail view in section on the plane indicated by the broken line 6—6 of Fig. 5. Figs. 7, 8 and 9 are detail views illustrating different modes of stitching wire on the edge of buckram hat frames and felt hats. Figs. 40 10 and 11 are detail views illustrating features of construction referred to hereinafter. Figs. 12 and 13 are detail views illustrating the connection between the looper and the main shaft. Figs. 14 and 15 are detail views 45 showing devices for rendering the feeder inoperative. Figs. 16, 17, 18 and 19 are detail views of the bed plate.

The machine shown in the drawings is 50 provided with a base *a*, adapted to rest upon a suitable table, and carrying a frame *a'* which, together with the usual arm *a''*, supports the working parts of the machine. The main shaft *b* is mounted in suitable bearings in the frame and is provided, as usual, with 55 a driving pulley *b'* and an eccentric *b''* which, through the pitman *b'''*, lever *b''''* and link *b'''*

imparts to the needle bar *c* its vertical reciprocations.

The needle bar *c*, arranged to carry the needle *c'*, as usual, is mounted to reciprocate vertically in a frame *d* arranged to oscillate about a vertical axis indicated at *d'* instead of a horizontal axis, as described in said patent. The frame *d* carries the needle bar with it in its oscillations, so that a zigzag 60 stitch may be formed, and provisions are made whereby the amplitude of the oscillations of the frame and the needle bar may be varied, to increase or diminish the width of the zigzag stitch, and even to be reduced 65 to zero so that the machine shall form an ordinary straight stitch, such provisions varying somewhat from those described in said patent, as will appear presently.

Upon a stud *e*, fixed in the frame *a'*, is 70 mounted a cam *e'* having secured thereto a gear *e''* which is engaged by a pinion *e'''* having half the number of teeth and mounted on the main shaft *b*, so that the cam receives a complete rotation for two complete 75 reciprocations of the needle bar. The cam *e'* is engaged by a stud *f'* on a curved, slotted lever *f*, suitably mounted on the frame of the machine. A link *f''*, which may be adjustably connected by a screw stud and 80 block *f'''* of usual construction, at any desired point of the lever *f*, so as to vary the throw of the parts operated thereby, as hereinafter described, connects said lever *f* with a sliding frame *g* mounted in suitable 85 guides, as at *g'* and *g''*, on the frame *a''*, so as to reciprocate horizontally. The upper forward end *g''* of the frame *g* is connected, preferably by a ball-and-socket joint *g''''*, (see Fig. 11) with an arm *d''* of the frame *d*. 90 By this means the frame *d*, and with it the needle bar, is oscillated about its vertical axis, the cam *e'* being so formed that the horizontal movement of the frame and needle bar takes place only when the needle 95 is at or near the highest point of its stroke and the point thereof is clear of the fabric, while during all other parts of its vertical movement the needle is held from lateral movement.

It is desirable to relieve the tension upon the thread during the lower portion of the stroke of the needle as set forth in said patent. The devices employed for the purpose differ somewhat, however, from those 110 shown in said patent. In the upper part of the frame *d* is mounted a short shaft *e''*.

To the left hand end of the same is secured an arm c^3 carrying a friction pad or foot c^4 which normally presses the thread against the guide plate c^5 . To the other end of the shaft c^2 is secured an arm c^6 with which a spring c^7 co-operates to hold the friction pad c^4 against the thread, the arm c^6 having an inclined or camlike projection c^8 with which the forward end of the lever b^4 co-operates 10 as it approaches the lowest part of its stroke to rock the lever and shaft against the pressure of the spring c^7 and slightly withdraw the friction pad c^6 from the thread so as to relieve the tension on the thread at the proper time.

The machine is provided with a presser foot h and a feeder h' , both of which perform their usual functions substantially in the usual way.

The looper i possesses the same function as the corresponding part in the construction described in said patent, but is operated in a somewhat different manner. It is secured to a hub i' grooved circumferentially as at i^2 and mounted upon a shaft k which, in the present machine, is solid and moves longitudinally within and rotates with the shaft b , which in this instance is hollow. In this manner the shaft b has a long bearing 20 in the base of the machine and the looper shaft k has a long bearing in the hollow shaft b . Upon the shaft b is mounted loosely a sleeve-like hub k' , grooved circumferentially as at k^2 and having a detachable 25 finger k^3 which engages a lug k^4 . The latter is secured detachably to the shaft k in a slot formed therein and slides in a longitudinal slot b^6 in the hollow shaft b . The sliding frame g has an arm g^5 which engages the 30 slotted hub k' and causes the same to reciprocate longitudinally, carrying with it the looper shaft and looper. Since the frame d carrying the needle bar and the looper shaft carrying the looper are thus both reciprocated through direct connection with the 35 sliding frame g and the amplitude of the reciprocations of the sliding frame is determined by the adjustment of the link f^2 in the lever f , it is obvious that the needle 40 and the looper must always bear the proper relation and that such relation is not disturbed by the adjustment of one of such parts. The proper rotation of the looper is insured by the engagement of the lug carried 45 by the looper shaft with the longitudinal slot in the hollow shaft b .

The work plate l is secured to the base of the machine in the usual manner, being slotted as at l' for the feeder h' and slotted 50 as at l^2 and provided with a bearing bridge l^3 for the throat plate m . Instead of having a wide opening to accommodate the lateral movements of the needle, whereby the work is not properly supported, the throat plate m 55 has a narrow slot m' and is made movable

in synchronism with the lateral movements of the needle, having a lug m^2 projected directly downward from the plate which engages the circumferential groove in the hub i' of the looper i , so that the throat plate 70 is reciprocated through direct connection with the looper and the proper relation between the needle, the looper and the slot in the throat is therefore at all times maintained.

In the machine shown in said patent the tension device for the thread was represented as mounted upon the arm a^2 , but in the present machine, as shown at n , it is mounted on the sliding frame g and therefore moves in synchronism with the oscillating frame b and the needle bar so that there is therefore no interference with the tension of the thread through a changing of distance between the needle bar and the tension device, as in the machine shown in said patent. The construction of the tension device is ordinary and need not be described herein.

The work guide or gage is so constructed 90 as to be adapted for the different kinds of work which are ordinarily done on machines of this character, such as the sewing of paper- or cotton-covered wire upon the surface of buckram hat frames, near the edge, 95 in which case the thread enters the material of the hat at each side of the wire, crossing to and fro over the wire, as shown in Fig. 7; or in sewing silk covered wire against the edge of felt hats, in which case the sewing thread 100 first enters the material of the hat and then catches the covering of the wire adjacent to the edge of the hat, as shown in Fig. 8; or in sewing paper or cotton covered wire against the edge of felt hats, to be afterward bound 105 over, in which case the sewing thread first enters the material of the hat and then passes outside of the wire, as shown in Fig. 9; and also so as to be adapted for wires of different thicknesses. The gage or guide is shown in 110 position on the machine in Figs. 1, 2 and 3, and is shown in detail in Figs. 4, 5 and 6. It comprises a supporting plate o which is suitably shaped and adapted to be secured 115 adjustably to the base of the machine having a longitudinal slot o' fitting upon a shorter rectangular projection o^2 of the base of the machine and held thereon by a thumb screw o^3 . Pivoted upon the plate o , as at p' , is a plate or lever p which at its left hand end is bent to form a guide p^2 , as shown most clearly in Fig. 1, for the edge of the hat or frame, and a thin finger p^3 to lie under the edge of the hat or frame and prevent it from 120 working under the guide p^2 . This guide also holds the wire from moving to the left and is not adjustable except as it is adjustable with the supporting plane o . A spring p^4 co-operates with the plate or lever p to hold it in its working position, as shown in 125 130

full lines in Fig. 1, but the plate or lever may be tilted into the position indicated by dotted lines in Fig. 1, to permit the release of the work at any time.

5 Mounted to slide on the supporting plate o are two outside guides q and r . The outside guide q is formed with a depending guide lip q' adapted to rest against the outer side of the wire, that is, against that side 10 which is the outer with respect to the body of the hat, and to hold it against the body of the hat and prevent it from being pushed away by the needle or otherwise. To accommodate wires of different thicknesses the 15 plate q is adjustable, being formed with an elongated slot q^2 to engage a screw stud q^3 , and being held in adjusted position by a thumb nut q^4 on the stud q^3 . The rear guide r is operative when the wire is to be stitched 20 against the edge of the hat brim and is arranged to be held in an inoperative position when the wire is to be stitched upon the brim, as shown in Fig. 7. The rear guide r is also formed with a depending guide lip 25 r' at its left hand end and has a limited sliding movement on the supporting plate o , being formed with an elongated slot r^2 for engagement with a holding and guide screw r^3 . A spring r^4 holds the guide lip normally 30 in its extreme left hand position, but permits the guide to yield to the right as the needle descends and, after its point has entered the cover of the wire, its thicker portion thrusts the wire farther to the right, 35 thus preventing the bending of the needle and the throwing of the needle out of proper alignment with respect to the looper. This yielding, rear guide, is operative when the machine is used upon such work as is indicated in Fig. 8, but when the needle passes 40 alternately on opposite sides of the wire, as in the character of work indicated in Figs. 7 and 9, then the rear guide must be drawn back out of the way so as to permit the 45 needle to descend at the right hand side of the wire as well as at the left hand side of the wire. A latch s , properly formed to engage the guide plate r , is pivoted on the supporting plate o to hold the guide in its right 50 hand position.

The feeder h' may be carried as usual by an arm h^2 which is pivoted at h^8 upon an arm h^4 . The to-and-fro or feeding movement of the feeder h' is effected by an eccentric h^5 on the main shaft through a link h^6 , and the vertical movement of the feeder, which causes it to rise into contact with the work during its forward movement and to descend away from the work during its rearward movement, is accomplished by an eccentric h^7 on the shaft b , which eccentric is embraced by a fork h^8 on the arm h^2 . This fork is subject to quite rapid wear and heretofore it has been a matter of considerable trouble to compensate for such wear. In

the present case, however, provision is made for readily compensating for such wear, as shown in Fig. 10, in which the eccentric h^7 is embraced by a two-part sleeve h^9 , the edges of the two parts not meeting. One 70 member h^{10} of the fork h^8 is detachable being held by a screw h^{11} . With this construction, whenever the amount of wear upon the eccentric has become objectionable, the member h^{10} is removed and its surface in contact 75 with the other part of the fork h^8 is filed off slightly so that when again applied its extremity causes the two parts of the sleeve h^9 to be pressed together somewhat more closely, thus taking up wear between the eccentric and the sleeve while the wear is also taken up between the sleeve and fork members. 80

In order that two or three stitches may be taken at the end of a piece of work in such a 85 manner as to prevent raveling, provision is made for stopping the forward feed of the work while the movements of the needle and looper continue, so that two or three stitches are taken one upon another and the thread 90 is thus fastened. To accomplish this purpose the feeder h' may be thrown out of operative position, as illustrated in particular in Figs. 14 and 15, which represent a modification of the construction shown in the 95 other figures of the drawings with respect to the mounting of the feeder. In this case the feeder h' is secured adjustably upon an arm h^{12} which is pivotally mounted, as at h^{13} , upon the arm h^2 . A spring h^{14} tends to 100 swing the arm h^{12} upon its pivot so as to throw the feeder h' down out of operative position, but the arm h^{12} may be held in proper operative position upon the arm h^2 by a latch which is shown as a disk h^{15} , cut 105 away as at h^{16} , and secured upon a short shaft h^{17} mounted in the arm h^2 , so that when the disk is in the position shown in Fig. 14 the arm h^{12} is held in operative relation with the arm h^2 between the disk h^{15} and a disk h^{18} on the other end of the shaft, but when the shaft h^{17} is partially rotated the cut-away portion h^{16} of the disk h^{15} permits the release of the arm h^{12} . For convenience in effecting the release of the arm 110 h^{12} so as to throw the feeder out of operative position, the shaft h^{17} is provided with an arm h^{19} adapted to be engaged by a fork h^{20} (see Fig. 15) carried by a sliding shaft h^{21} . The latter, in turn, is engaged by a hand lever h^{22} which may be conveniently placed for operation. 115

The mode of operation of the several parts of the improved machine has been sufficiently explained in connection with the description of such parts and the operation of the machine as a whole will therefore be readily understood. 125

It will be obvious that while the coöperation of all of the several improvements 130

herein described increases the efficiency and convenience in use of the machine, nevertheless some of such improvements are capable of being used without others, and it will also be obvious that changes in details of construction and arrangement of the several parts of the machine may be made to suit different conditions of use. The invention, therefore, is not limited to the details of the particular construction shown and described herein.

I claim as my invention.

1. In a sewing machine, the combination of a supporting arm, guides thereon, a sliding frame mounted on said guides, means to reciprocate said frame, a swinging needle bar frame, the forward end of the sliding frame being directly engaged through a joint with the needle bar frame, a needle bar, means to reciprocate the needle bar, a looper, a looper shaft, and a main shaft supporting the looper shaft, the sliding frame having a direct engagement with the looper shaft to reciprocate the same.
2. In a sewing machine, the combination of a supporting arm, guides thereon, a swinging needle bar frame, a reciprocating looper and looper shaft, a sliding frame mounted on said guides and directly engaging the needle bar frame through a joint and the looper shaft, whereby they are moved in the same relation, and actuating means for said sliding frame, comprising a cam, a slotted lever and a link.
3. In a sewing machine, the combination of a supporting arm, guides thereon, a swinging needle bar frame, a reciprocating looper, a sliding frame mounted on said guides to which the needle bar frame and the

looper are operatively connected, whereby they are moved in the same relation, a cam, a slotted lever actuated by said cam, and a connection, shiftable in said slotted lever, between the lever and the sliding frame.

4. In a sewing machine, the combination of a supporting arm, guides thereon, a sliding frame mounted on said guides, a swinging needle bar frame operatively connected with the sliding frame, a needle bar, means to reciprocate the needle bar, a reciprocating looper operatively connected with the sliding frame, and actuating means for said sliding frame, comprising a cam, a slotted lever and a link.

5. In a sewing machine, the combination of a hollow main shaft having a longitudinal slot, a looper, a looper shaft mounted to reciprocate in and rotate with the main shaft and having a lug entering the slot in the hollow shaft, a sleeve loosely surrounding the main shaft, a finger detachably secured to the sleeve and engaging the lug, and means to reciprocate said sleeve.

6. In a sewing machine, the combination of a supporting frame and arm, a swinging needle bar frame supported by said arm, a needle bar, a sliding frame also supported by said arm and connected with the needle bar frame, a lever operatively connected to the needle bar and a tension device mounted on the sliding frame and moving therewith.

This specification signed and witnessed this 6th day of August, A. D. 1908.

LOUIS BULASKY.
